UNITED STATES PATENT OFFICE.

ALBERT A. HOFMANN, OF BLOOMINGTON, ILLINOIS.

FOUNTAIN-PEN.

SPECIFICATION forming part of Letters Patent No. 623,474, dated April 18, 1899.

Application filed February 15, 1898. Serial No. 670,395. (No model.)

To all whom it may concern:

Be it known that I, ALBERT A. HOFMANN, residing at Bloomington, in the county of McLean and State of Illinois, have invented a new and Improved Fountain-Pen, of which the following is a specification.

In the use of the ordinary forms of fountain-pens more or less annoyance is experienced in determining when the ink in the fount is entirely or about exhausted.

The object of this invention is to provide the ordinary forms of fountain-pens now in general use with means whereby the quantity of ink can be instantly ascertained, which means are of such character as not to increase the cost of manufacture of such pens nor render them in any way less effective in their use.

The invention embodies certain features of construction and arrangement of parts, such as will be first described in detail and then specifically pointed out in the appended claim, reference being had to the accompanying drawings, in which—

Figure 1 is a perspective view of my improved fountain-pen. Fig. 2 is a longitudinal section of the same. Fig. 2^a is an enlarged detail sectional view taken longitudinally of the fountain-pen and illustrating the manner of mounting the transparent members.

Fig. 3 is a horizontal section taken on the line 3 3 of Fig. 2. Fig. 3^a is a transverse sectional view on the line 3^a 3^a of Fig. 1.

By referring to the drawings, in which like numerals indicate like parts in the several figures, 1 indicates the fount or holder, 2 the screw-cap, and 3 the valve or feed-stem, all of which in their general arrangement and operation may be of any approved and well-known construction.

The fount or holder in the present form of pen has one or more slits or openings 2^a, which may extend a part or the full length of the fount. In these openings are fitted members 4 of glass, mica, or other transparent material, in practice preferably one-eighth of an inch wide.

To provide a simple and economical construction of the holder, the slots 2^a are extended through the lower end of the fount or

holder 1 and have grooves in the edges and the upper end, forming slideways for the transparent members 4, which snugly fits such ways and are held fluid-tight by packing-strips, as clearly shown in Figs. 2^a and 3.

By extending the openings 2^a through the lower end of the holder it is manifest the transparent slides and packing members can be readily slipped in place and the slides held fluid-tight by the friction of the said packing-strips, it being also understood that the feed-stem 3 when screwed home serves as a positive lock to prevent the members 4 from dropping out of the openings 2^a, and it is provided with an annular shoulder which abuts against the end of the fount or holder and the outer end of the said members 4. By this construction the transparent members 4 are detachably secured in the grooves of the fount or holder.

While I have shown in the drawings the fount-body formed with a number of slits and pockets, it is manifest such body need have but one slit, and while I prefer to extend the slits the full length of the fount-body they need not extend the entire length, but up a suitable distance from the pen or feed end to admit of readily determining when the fluid is about exhausted from the fount.

I am aware that a writing device formed of a glass body has been provided, in which fluid is always in view. This form of writing device is, however, no substantial substitute for a fountain-pen, which must of necessity withstand rough usage and be made of a material which will not readily break in handling or falling onto a solid body.

My invention is especially applicable to fountain-pens in which the fount is made of metal or hard rubber and non-transparent, and its main purpose is to provide a fount-body of this character with a simple and inexpensive means for always bringing in view the contents of the fount without increasing the cost of the ordinary forms of founts or affecting their strength or durability.

The transparent pockets are to be so attached to the fount as to form practically a part thereof and are not in the nature of independent gage-glasses.

Having thus described my invention, what I claim, and desire to secure by Letters Patent, is—

In a fountain-pen, the combination of a fount, having a longitudinal slit extending inward from its front end and provided with longitudinal grooves in its side and end walls, the transparent member 4, fitted in the grooves of the fount and having its side and inner end edges fitting against the walls of the slit, its outer end being flush with the front

end of the said fount, and the feed-stem mounted on the fount and having a shoulder abutting against the front end of the fount and the outer end of transparent member and detachably securing the latter in the former, substantially as described. 15

ALBERT A. HOFMANN.
